US00D954703S

(12) **United States Design Patent** (10) **Patent No.:** **US D954,703 S**
(45) **Date of Patent:** **** Jun. 14, 2022**

(54) **PORTABLE INFORMATION TERMINAL**

(71) Applicant: **SEMICONDUCTOR ENERGY
LABORATORY Co., Ltd.**, Atsugi (JP)

(72) Inventors: **Yosuke Tsukamoto**, Atsugi (JP);
Shunpei Yamazaki, Atsugi (JP);
Kazuhiko Fujita, Atsugi (JP); **Akio
Endo**, Atsugi (JP)

(73) Assignee: **Semiconductor Energy Laboratory
Co., Ltd.**, Kanagawa-ken (JP)

(**) Term: **15 Years**

(21) Appl. No.: **35/508,746**

(22) Filed: **Aug. 30, 2019**

(80) **Hague Agreement Data**

Int. Filing Date: **Aug. 30, 2019**

Int. Reg. No.: **DM/204873**

Int. Reg. Date: **Aug. 30, 2019**

Int. Reg. Pub. Date: **Mar. 6, 2020**

(30) **Foreign Application Priority Data**

Mar. 8, 2019 (JP) 2019-004892
Mar. 14, 2019 (JP) 2019-005376

CLAIM

The ornamental design for portable information terminal, as shown and described.

DESCRIPTION

1. Portable information terminal
- 1.1 : Perspective
- 1.2 : Perspective
- 1.3 : Perspective view showing changed state
- 1.4 : Perspective view showing changed state
- 1.5 : Perspective view showing changed state
- 1.6 : Front
- 1.7 : Back
- 1.8 : Right
- 1.9 : Left
- 1.10 : Top
- 1.11 : Bottom

(Continued)

The portable information terminal can be used in the three-folded state, the two-folded state, the unfolded state, or the state bent in an arbitrary shape, as seen in reproductions 1.1 to 1.11.

1 Claim, 11 Drawing Sheets
